UNITED STATES PATENT OFFICE.

MILTON B. REACH, OF SPRINGFIELD, MASSACHUSETTS, ASSIGNOR TO A. G. SPALDING & BROS., OF NEW YORK, N. Y., A CORPORATION OF NEW JERSEY.

GOLF CLUB.

Application filed June 24, 1925. Serial No. 39,260.

To all whom it may concern:

Be it known that I, MILTON B. REACH, a citizen of the United States, and resident of Springfield, in the county of Hampden and State of Massachusetts, have invented certain new and useful Improvements in Golf Clubs, of which the following is a specification.

The invention relates to means for securing metallic shafts of golf clubs to the heads thereof, and it consists in the features hereinafter pointed out and particularly claimed.

In the accompanying drawing

Figure 1 is a sectional view of a golf club head with the shaft in place.

Fig. 2 is a sectional detail view.

Fig. 3 is a detail view showing the lower end of the shaft before the cord winding is applied thereto, with the upper portion partly broken away.

In these drawings 1 indicates a golf club head of any ordinary construction and 2 indicates a hollow metallic shaft. This shaft extends into the neck portion 3 of the club as usual. It is provided with cross cuts or kerfs 4 which extend through the wall of the metal tube and in a direction transverse to the tube. These kerfs are disposed at separated points along the shaft at that portion which is located within the socket of the head, and surrounding the metallic shaft there is a cord of ordinary material such as cotton, this being wound spirally on the exterior of the shaft and at intervals the cord passes through the transversely extending kerfs. Within the shaft there is a filler piece 5 preferably of wood. After the cord is wound as just described on the exterior of the metallic shaft, the said shaft is dipped in glue which will saturate the cord, and at the points where the kerfs or cuts occur the glue will impregnate the cotton cord and also contact with a wooden filler, and make a firm connection between the cord and the filler.

After dipping, as just described, in the glue, the shaft with the cord wound thereon saturated with the glue is inserted in the socket of the golf head so that the glue will make a firm union between the shaft and the wooden wall of the socket of the head.

At the points where the cord passes through the kerfs a mechanical connection is made between the cord and the shaft which will resist a tendency for displacement in a direction longitudinally of the shaft, this being in addition, of course, to the union affected by the glue itself.

The shaft will extend through the socket all the way to the lower face of the head where the wooden core will be exposed so that if it is desired to disconnect the shaft from the head this core of wood can be bored out, and then by the introduction of hot water into the space thus provided the glue connection can be melted for the withdrawal of the shaft from the head.

It will be seen that the formation of the shaft ready to receive the cord can be performed by a very simple act expeditiously by simply cross cutting through the wall of the hollow shaft.

The end of the cord may be passed through an opening formed transversely through the lower end of the shaft and the core as at 6 and the winding then will be carried on from this point.

I claim as my invention:

1. In combination with a golf club head, a hollow shaft having notches disposed at different points along the same, a cord wound spirally about the shaft, and at intervals entering the said notches, the said cord being saturated with glue and contacting with the interior wall of the socket of the head, substantially as described.

2. In combination in a golf club, a head having a socket, a hollow shaft having a wooden or like core at its lower end and openings in the wall of the shaft, a cord wound spirally upon the exterior of the shaft and at intervals passing through the said openings to contact with the core, said cord being saturated with glue, which unites the core and the cord with the interior wall of the socket of the head, substantially as described.

3. In combination with a golf head having a socket, a metallic shaft having a wooden core at its lower end and provided with kerfs or cross cuts through its wall, a cord wound on the exterior of the metallic

shaft and at intervals extending through the said transverse kerfs, said cord being saturated with glue, which unites the shaft structure with the interior wall of the socket of the head, substantially as described.

4. In combination, a golf club head, a shaft having transverse spaced notches, a

cord wound spirally around the shaft and at intervals entering the said notches, said cord being adhesively secured to the interior 10 wall of the socket of the head.

In testimony whereof I affix my signature.

MILTON B. REACH.
